OF WADSWORTH, OHIO, A CORPORATION OF OHIO.

PROTECTING-STRIP FOR MATCH AND OTHER BOXES.

1,106,380.

Specification of Letters Patent. Patented Aug. 4, 1914.

Application filed November 21, 1913. Serial No. 802,283.

To all whom it may concern:

Be it known that I, ADAM J. HALLER, a citizen of the United States, residing at Wadsworth, in the county of Medina and State of Ohio, have invented a certain new and useful Improvement in Protecting-Strips for Match and other Boxes, of which the following is a full, clear, and exact description.

10 This invention relates to a protecting strip to be applied over articles within a box, so as to prevent the escape of the contents of the box, and yet admit of the withdrawal of the individual articles without 15 removing the strips; the invention being primarily designed for use in a match box of the type where the matches are contained in a tray that is to be inclosed or covered by a slide or shuck.

20 The invention is herein shown and will be explained in connection with a match box of the character last mentioned, although the invention is not limited to its use in connection with matches, but is applicable to 25 other boxed articles than matches.

The invention consists of a protecting strip for match and other boxes, constructed to completely cover the contents of the box from side to side and end to end, excepting 30 for a portion of one side where the strip is so formed as to expose sufficient of the contents to enable a person to remove the contents piece by piece, without removing or substantially disturbing the protecting strip, 35 as I will proceed now to explain and then claim.

In the accompanying drawings illustrating the invention, in the several figures of which like parts are similarly designated, 40 Figure 1 is a perspective view of a common form of shuck and tray match box, the shuck and tray being detached, the tray being shown as filled with matches, and the protecting strip of this invention applied. 45 Fig. 2 is a perspective view of the protecting strip detached. Fig. 3 is a top plan view of a filled tray with the protecting strip in place, and one of the matches in process of being removed. Fig. 4 shows in 50 plan view a number of protecting strips and also illustrates an economical method of forming these strips from a strip of cardboard or equivalent material.

The tray 1 and shuck 2 may be of any approved construction, and the matches 3 55 are arranged in the tray in any usual way, it being customary in the best practice to arrange the matches with the heads 4 in one direction, so that their handle ends 5 may be exposed together. 60

It is old in the art to apply a protecting strip to matches arranged in a tray, and such protecting strip is usually a strip of cardboard or boxboard or other equivalent material of about one-half the width of the 65 tray, and having its ends bent at right angles so as to be tucked in the ends of the box between such ends and the contents, but these protecting strips leave not only the 70 handle ends of the matches exposed, but also the heads of the matches, the main purpose of such narrow strips being to retain the matches while the tray is being inserted in the shuck; and it is likewise customary for 75 the users in the first instance to remove the protecting strip and throw it away. It has also been proposed to use a protecting strip that will cover substantially the whole contents of the box, and which is designed not to be removed, but in order to get at the 80 contents of the box, it is necessary either to move or more or less entirely remove such strip.

The present invention is designed to provide a protecting strip which will cover substantially the entire contents of the box, and more particularly the heads of the matches in the box, while exposing sufficient of the contents of the box to make such contents accessible for removal, without disturbing 90 the strip. For this purpose the protecting strip 6 is made of any suitable comparatively stiff material, of substantially the length and width of the box, and has end flanges 7 of sufficient length to be tucked in 95 between the ends of the box and the contents to hold the strip in place, and the sides of these flanges are beveled at 8 to facilitate the insertion of the flanges between the ends of the box and the contents of the box. A 100 portion of one side of the strip is cut away as at 9, so as to expose sufficient of the contents of the box to permit the user to remove such contents without disturbing the protecting strip. This operation is illustrated in detail in Fig. 3 in which it will be 105

seen that the cut away portion 9 does not extend the full length of the strip, but is formed between the ends, so as to leave the full-width end portions 10, and these end portions serve to hold the strip against transverse displacement while not interfering in the least with the users' access to the contents of the box, so as to remove such contents piece by piece or article by article.

10 The shape of the cut out portion is immaterial, but its curvilinear contour shown will best preserve its integrity in use.

The protecting strip completely fills the top of the box from end to end and from side to side, excepting for the cut out portion, and it so fills the top that it cannot be displaced accidentally, and cannot work out of place; it also covers the heads of the matches and always exposes the handle ends 20 of the matches, so that not only may the matches be removed from the box one by one, but it would be difficult for a person to grab a handful of matches from a box. The strip also prevents the spilling of the 25 matches or contents of the box, when the box is handled roughly.

As indicated in Fig. 4, these protecting strips may be economically cut from a straight blank with a minimum of waste, 30 and the strip may be printed appropriately, the portions of the strip between the lines 11 serving to receive any desired advertisement or other printed matter. It will be observed also that the only waste in blanking 35 out the strips is at the points 12, where the beveling of the ends 7 is done. The strips are severed on the lines 13 at the bottoms of the flanges, and also severed along the lines 14, and each strip is scored along the transverse dotted lines 15, on which dotted lines the flanges are bent.

What I claim is:—

1. A protecting strip for match and other boxes, of a length and width substantially coincident with the length and width of the box and thereby held from lateral displacement, and having end flanges adapted to be interposed between the contents and the ends of the box, and having a cut away portion at one side sufficiently large to expose a portion of some of the contents to render such contents accessible.

2. A protecting strip for match and other boxes, of a length and width substantially coincident with the length and width of the box, so as positively and at all times to cover the underlying contents of the box and having end flanges adapted to be interposed between the contents and the ends of the box, and having a cut away portion at one side sufficiently large to expose a portion of some of the contents to render such contents accessible, the end flanges having beveled edges to facilitate the insertion of the strip.

3. A protecting strip for match boxes, of substantially the length and width of the inside of the box, and having end flanges adapted to be inserted between the matches and the ends of the box, and having one side cut away between its ends so as to expose the handle ends of the matches and leave end portions at opposite ends of the cut away portion of the full width of the box, the strip serving to cover the heads of the matches at all times when within the box.

In testimony whereof I have hereunto set my hand this 18th day of Nov., A. D. 1913.

ADAM J. HALLER.
